UNITED STATES PATENT OFFICE.

FRED ELMER GALLAGHER, OF TOLEDO, OHIO.

BUILDING-UNIT MACHINE.

Application filed January 18, 1924. Serial No. 687,095.

An object of this invention is the production of a machine of such construction that the parts constituting the same will in a continuous cycle of operative movements, produce concrete building units, such as blocks, bricks, building tile, chimney blocks, pier blocks, floor tile, either ornamental or plain.

With the above broadly stated object in view, and many others which will present themselves in the following disclosure, reference is to be had to the drawings which accompany and which form part of this application.

In the drawings:—

Figure 1 is a side elevation of a building unit machine in accordance with this invention.

Figure 2 is an elevation looking towards the opposite side of the machine.

Figure 3 is a top plan view.

Figure 4 is a central vertical longitudinal sectional view therethrough.

Figure 5 is a sectional view approximately on the line 5—5 of Figure 3, but showing the feed hopper moved over the mold box.

Figure 6 is a sectional view approximately similar to Figure 5 showing the mold box projecting outwardly as when a block has been formed therein and is to be removed therefrom.

Figure 7 is a detail sectional view approximately on the line 7—7 of Figure 1.

Figure 8 is a front elevation of the substantially U-shaped roller carrying member, the rails engaged between the rollers and blocks of the said members being in section as is also a portion of the frame.

Figure 9 is a transverse sectional view approximately on the line 9—9 of Figure 6.

The improvement includes a suitable frame constituting a base that includes parallel sides and a rear connected end and uprights and both horizontal and transverse elements secured thereon, as well as brace means for the latter.

On one side of the frame there is a wheel 1 which may be started or stopped at any point in the operation of the machine, and is placed in such position to bring the control lever therefor within easy reach of the operator. The control lever is indicated by the numeral 1'. The wheel 1 is mounted on a suitable shaft 2 that is journaled in suitable bearings on the frame, adjacent to the rear thereof. On the end of the shaft, opposite that on which the wheel 1 is arranged,

there is keyed a pinion 3, and this pinion is in mesh with a gear 4 keyed on a shaft 5 that is journaled in bearings on two of the longitudinal members of the frame, the said shaft extending beyond its bearings. Keyed on the inner end of the shaft 5 there is a pinion 6 which is in mesh with a gear 7. This train of gears supplies the power to pack the block and is so arranged that a mold of blocks, tile or brick are made in one cycle of the shaft 8 on which the gear 7 is keyed. The shaft 8 is journaled in suitable bearings on the frame and extends beyond the sides of the said frame. The gears and pinions are so proportioned that the pinion 3 turns four times while the gear 4 turns once and the pinion 6 turns four times while the gear 7 completes a revolution, so that the pinion 3 completes sixteen revolutions to one of the gear 7. This ratio may, of course, be increased any number of times to give greater power, if needed, by arranging on the various shafts different sized gears and pinions.

On one end of the shaft 8 there is a quick action cam 9 which turns in a forward direction on the frame and which is designed to contact with a roller 10 on an arm 11 to push the feed hopper 12 over the mold box 13 to fill the latter with the proper amount of material to make a mold of blocks, tile or bricks. These parts are so constructed that a quarter turn of the shaft 8 places the material in the mold box, while in other molding machines with which I am acquainted, several movements are required to accomplish this purpose. The roller carrying arm 11 is secured on a short shaft 14 that is journaled in suitable bearings on the frame, the said shaft carrying a rocker arm 15 to whose sides are pivoted links 16 that are in turn pivoted to a rod 17 secured between angle rails 18. These rails have their outer ends fixedly secured to the sides of the feed hopper 12.

Secured on the frame there is a substantially U-shaped member 19 which has pivotally connected to its upright arms, on the inner faces thereof, rollers 20 and blocks or enlargements 21 above the rollers. Other and outer rollers 21' also support the rails. The rails 18 travel over the rollers and are prevented from upward movement by the blocks or enlargements 21. The U-shaped member or bracket 19 has its upper element disposed above the links 16, and it will be

apparent that when the cam 9 is moved to swing the roller carrying arm 11 in one direction, the shaft 14 will be rocked, causing its arm 15 to impart movement to the 5 links 16 and thus move the feed hopper over the mold box 13 or away therefrom. The cam 9 is so constructed that the feed hopper 12 is halted for a considerable desired period in either of its positions.

10 The feed hopper 12 is in the nature of a rectangular member, and normally rests on a plate 22 secured between the inner longitudinal members of the frame, and the said plate provides a closure for the open bottom of the slidable hopper 12. From its upper rear corner there is extended from the feed hopper 12 a plate, in the nature of an apron 23. The apron is stepped, and the upper elevated rear portion thereof is, for 15 distinction, indicated by the numeral 24.

Secured by means 25 to the uprights adjacent the forward end of the frame, and disposed directly over the feed hopper and its apron, when the latter is in normal retracted position, there is a material or directing hopper 26. The apron 23 and its extension is of a size to cover the bottom of the material directing hopper 26 when the feed hopper is moved outwardly therebelow, 20 and the shoulder provided by the stepped portion of the apron affords a means for wiping the material from the bottom of the directing hopper to deliver the same into the feed hopper.

25 Journaled in bearings 27 in longitudinal plates 28 secured to the frame uprights 29, there is a shaft 30. On the shaft 30 there is freely mounted a mixing bin 31. The portion of the shaft received in the bin is provided with a spirally arranged series of material mixing fingers or arms 32 and secured on the plates 28 to the rear of the bin there is a platform 33 on which the operator stands for directing the material into the 30 bin. Of course, this may be automatically accomplished. I secure to one side of the bin 31 an angularly disposed lever 34 which is in contact with the platform 33 for holding the bin from accidental turning in a forward 35 dumping direction.

Keyed on one end of the shaft 30 there is a pulley wheel 35, around which is trained a belt 36 that is likewise trained around a pulley wheel 37 on the shaft 5. Thus the 40 turning of the drive shaft 2 will impart motion to the finger carrying shaft 30 in the mixing bin 31 so that material therein will be effectively mixed. There is arranged between the bin and the shaft 30 lever operated clutch means 38 whereby the mixing device may be stopped or started. The lever 45 34 is employed for dumping the mixing bin to deliver the contents therefrom into the material directing hopper 26 and from thence into the feed hopper 12.

Below the outer edge of the plate on which the movable feed hopper rests, there is secured to the referred to uprights on the frame a plate 39. This plate 39 has vertically disposed elongated slots or openings 40 adjacent to its ends, and an inner series of substantially rectangular openings 41, the purpose of which will presently be apparent.

The mold box 13 includes a frame which 75 comprises side members 42 connected together by an approximately central transverse partition 43 and having their lower corners provided with inwardly extending cleats forming rails 44. The partition is 80 notched in a line with the said rails. The mold box, outward of its partition has fixed in bearings upon the lower sides thereof a shaft 45 that is journaled in suitable bearing openings in the sides of the frame, and 85 the turning of this shaft will swing the mold box to either horizontal or substantially vertical positions, in a manner which will presently be described.

The slidable bottom of the mold box 90 includes a pair of spaced bars 46 that ride on the rails 44 and that pass through the referred to openings in the partition 43. These bars are connected together at their ends adjacent to the plate 39 by a plate 47, and this plate, in reality, provides the bottom 95 of the mold box. At the rear of the plate and secured to the bars 46 there are uprights 48 which are arranged in slight contacting engagement with the side members 42 of 100 the mold box. These uprights provide rests for a pallet 49, and suitable latching means 50 may be and preferably are employed for locking the pallet on the rests or uprights 49. The pallet 49 is provided with openings 105 corresponding in number and size with the openings 41 in the plate 39, and aligning therewith when the mold box is in normal horizontal position. When in such position the plate 39 provides one of the end walls 110 for the said mold box.

The side members 42 of the mold box are approximately centrally grooved longitudinally on their outer faces, as indicated by the numeral 51, the said grooves terminating in notches 52 at the outer ends of the sides 115 42. Disposed for slidable movement in the grooves 51 there are plates or bars 53, the said bars having their outer ends connected by a bar 54 of a size to be received in the 120 notches 52. The bars 53 in reality provide rails and are of a length approximately equalling one-half or less than one-half of that of the mold box. The rails 53 have secured on their outer faces upstanding plates 55, and either formed with or secured to these plates there is what I will refer to as the finishing plate 56 for the material in the mold box. The outer connecting element of the rails 53, referred to as the bar 54, has 125 130

secured thereon equi-distantly spaced packing fingers 57. These fingers are received through the openings in the partition plate of the mold box and are movable into the openings 41 in the plate 39.

The side members of the mold box, from the outer end thereof, and below the grooves 51 are notched longitudinally, as at 58, the said notches receiving therein a connecting 10 plate or bar 59 for the bars 46 of the movable bottom plate 47 of the mold box. Either the bar 59 or the bars 46 have outstanding headed studs 60 which pass through the notches 58 and which also pass through 15 elongated slots 61 in the outer ends of links 62. The inner ends of these links are fixed to a shaft 63 that is journaled in the sides of the main frame. The links are arranged at a downward angle with respect to the 20 mold box.

The connecting bar 54 for the rails 53 has projecting ends which are reduced and rounded and which receive thereon links 64. Suitable means 65 is provided for retaining 25 the links on the trunnions provided on the ends of the said bar 54. These links pass through the slot 40 in the plate 39, and are pivotally connected to normally angularly disposed links 66 secured on a shaft 67 that 30 has its ends journaled in suitable bearings on the side members of the main frame. The shaft 67 has thereon an angle arm 68 on whose outer end there is journaled a roller 69.

35 On the inner face of the gear wheel 7, which is mounted on the shaft 8, there is fixed a cam 70 designed to ride over the roller 69 to swing the arm 68 to turn the shaft 67 and through the medium of the 40 links 66 secured thereon, to influence the links 64 to move the rails 53 and the finishing plate 56 carried thereby over the top of the mold box, and to likewise swing the mold box to either its horizontal or upward 45 angular position. When moved to its latter position the fixed slotted links 62, engaging the studs 60 on the movable bottom of the mold box will influence the same outwardly therefrom so that the pallet and the 50 block formed thereon may be readily removed therefrom for drying or stacking, and a similar pallet may be arranged upon the rest provided by the uprights on the said movable bottom of the mold board. The 55 turning of the shaft 8 will further influence the cam to swing the roller carrying arm and the shaft 67 in an opposite direction which will cause the parts to move reversely to that just described, so that the top of the mold 60 box will be open. As previously intimated, the operation is so timed that after the dumping of the material from the bin into the directing hopper 26 and from thence into the feed hopper 12 the latter will be moved 65 outwardly so that the material therefrom

will be deposited into the mold box. As the feed hopper is returned to initial position the finishing plate will be moved over the material in the mold box and with the movement of the said plate the packing fingers 70 will be forced through the said material. This has both a wiping and a squeezing effect upon the block in the mold box so that water will be removed from the material, and the building unit will be in a practically 75 dry state when removed with the pallet from the mold box.

To accomplish the movement of the mold box and the parts associated therewith there is fixed on one end of the shaft 45 to which the mold box is connected a drum wheel 71 around which there is trained a flexible element in the nature of a cable or chain 72. The cable has its ends connected respectively to the ends of lever arms 73 and 74. 80 Both of these arms are journaled on a stub shaft 75 that extends from the frame, and the outer and shorter lever arm 73 has on its free end a roller 76 that is in contacting engagement with a cam 77 fixed on the 85 outer end of the shaft 8. The free end of the inner lever arm 74 is weighted, or may have adjustably secured thereon a weighted element whereby the said end of the lever is always moved in a downward direction, and 90 this weighted end of the lever will return the mold box to horizontal and open position when the cam 77 has traveled off of the roller 76 on the arm 73. This is, of course, incident to the weighted end of the arm influencing the same downwardly and exerting 95 a pull on the flexible element or cable 72 to wind the same around the drum 71 and to cause the lead of the said cable to exert a pull against the roller carrying lever 73. 100

It is thought that the foregoing description, when taken in connection with the drawings will fully set forth the construction and operation of my improvement to those skilled in the art to which the invention relates and that further detailed description will not be required. It will, of course, be apparent that fancy facings, such as marble dust, granite, quartz, etc., may be employed to face the unit without the use 110 of glue and further that my apparatus is automatic in action, quick in operation and thoroughly efficient for its purposes. I wish it further understood that the nature of my improvement is such as to necessarily render 115 the same susceptible to changes and modifications, and therefore the invention is limited only by the scope of the appended 120 claims.

Having described the invention, I claim:— 125

1. In a concrete building molding machine, a bin, means for mixing concrete therein, a slideable hopper below the bin, means delivering mixed concrete thereinto when the bin is turned, means for turning 130

the bin when the hopper is in concrete receding position, a mold box outward of the bin, means moving the hopper over the mold box to deposit the concrete therein, means
6 compressing the concrete in the mold box after the hopper has been returned to initial position, means wiping the surplus concrete from the mold box, means for tilting the mold box to permit of the removal of the
10 molded article therefrom, and means returning the mold box and the elements associated therewith to initial position.

2. In a concrete molding machine, a frame, a bin thereon, a shaft on which the
15 bin is supported, beater arms on the shaft, means for revolving the shaft, means for tilting the bin to deposit the concrete therefrom, a receiving hopper in which the concrete is received, a slidable hopper therebelow receiving the concrete therefrom, means comprising a stepped apron on the inner corner of the slidable hopper for closing the bottom of the receiving hopper, a mold box outward of the slidable hopper over which
20 the latter is movable to deposit concrete thereover, means compressing the concrete in the mold box to remove moisture therefrom, means for wiping superfluous concrete from the mold box and for facing the molded
25 article therein, means for tilting the mold box to permit of the removal of the molded article therefrom when the slidable hopper is returned to initial position, and means for returning the mold box and elements associated therewith to initial position immediately prior to the movement of the slidable mold box over said hopper.

4. In a concrete molding machine, a frame including an apertured face plate, a mold box 70 pivotally supported on the frame and normally in contact with the plate, an apertured pallet removably received in the mold box, means for delivering mixed concrete into the mold box, slidable fingers movable 75 through the openings in the pallet and plate for compressing the concrete in the mold box, means for operating said compressing means, means slidable over the mold box for wiping and facing the molded article there- 80 in movable in timed relation with the fingers, means for tilting the mold box to permit of the removal of the pallet and molded article therefrom, means for retracting the fingers and the wiping means when the mold 85 box is tilted, and means for returning the mold box and the elements associated therewith to initial position to permit of the reception of additional concrete in the mold box.

3. In a concrete molding machine, a frame, a shaft journaled on the top thereof, a concrete receiving bin journaled on the shaft, beater arms on the shaft for mixing concrete in the bins, means for revolving the shaft, means for tilting the bin, a hopper in which the mixed concrete is received, a slid- 40 able hopper therebelow receiving the mixed concrete therefrom, a rearwardly projecting
45

In testimony whereof I affix my signature.
FRED ELMER GALLAGHER.
